J. P. DUBOSH.
CONTAINER FOR STRING NAILS.
APPLICATION FILED APR. 30, 1918.

Patented June 17, 1919.

INVENTOR:
John P. Dubosh
by his attorney
Charles J. Richardson

UNITED STATES PATENT OFFICE.

JOHN P. DUBOSH, OF FALL RIVER, MASSACHUSETTS.

CONTAINER FOR STRING-NAILS.

1,307,042.

Specification of Letters Patent. Patented June 17, 1919.

Application filed April 30, 1918. Serial No. 231,623.

To all whom it may concern:

Be it known that I, JOHN P. DUBOSH, a subject of the Austro-Hungarian Government, residing at Fall River, in the county 5 of Bristol and State of Massachusetts, have invented certain new and useful Containers for String-Nails, of which the following is a specification, reference being had therein to the accompanying drawings.

10 The objects of my invention are to provide, first, means whereby a package of coiled string-nails may be released from its fastenings, be retained in coiled form, and be unwound without becoming snarled or 15 broken; and, second, means whereby each of two or more separate packages of coiled string-nails may be released, retained and unwound without becoming snarled or broken.

20 My invention may be embodied in forms that are simple in construction, and inexpensive to manufacture.

It is designed primarily for use in connection with a device, which I call a hand-nailer, but its use is not necessarily limited 25 thereto; said hand-nailer being fully described and claimed in application for Letters Patent for "device for driving or positioning nails or the like," No. 231,624, and 30 filed by me, April 30, 1918.

With my invention, the hand nailer may be used until the coils of one size of nails are, or are not, entirely used up; or, if after using nails of one size, any other size 35 is required, then the nailer may have fed into it a string of longer or shorter nails.

In fine, by means of my invention, there is at hand means whereby the operator has a supply of string-nails of the required 40 size or sizes.

In the drawings illustrating the principle of my invention and the best embodiment of the same in operative structure,

Figure 1 is a perspective view of my invention arranged upon a standard, and 45 shows how my hand-nailer, indicated in dotted lines, may be supplied with nails from any one of a number of containers for coils of string-nails;

50 Fig. 2 is an enlarged view, in elevation, and partly broken away to show the coils of a package of string-nails within a container, and a freed portion of the string partially withdrawn from the container;

Fig. 3 is a cross section, on line 3—3, 55 Fig. 2;

Fig. 4 is a side view of an empty container, with ring-cover separated therefrom;

Figs. 5 and 6 are fragmentary views, illustrating means for removably securing the ring-cover to the cylindrical portion of the container.

A container 1, for a package of coiled string-nails 2, Figs. 2 and 3, is provided. 65 It has a hollow metallic cylinder 3 with a base 4; and a drum portion 5, secured to the base, and in the longitudinal axis of the cylinder. To the exterior end of the drum 5 is fixed a circular plate 6, parallel with 70 the base 4 of the cylinder; the outer edge of the plate being provided with an outwardly extending nail-guiding flange 7. A ring-cover 8 with an inner edge flange 9, and an outer edge flange 10, extending in- 75 wardly, serves to close all of the ring opening end of the container, excepting the space 11 left between the inner flanged edge of the ring-cover 9, and the nail guiding flange 7, of the drum, and serving as an outlet 80 space through which the freed strand of nails 12 may be withdrawn.

This ring-cover 8 may be removably secured to the sides 3 of the container, by means of clips 13, 14, Figs. 5 and 6, that 85 may be moved into or out of interlocking engagement by twisting the ring-cover 8 in relation to the cylindrical sides 3 of the container.

It will be noted, see Figs. 2 and 3, that 90 the container is made of such a size that the diameters of the outside coils of the package, and the inside of the container, are the same; that the inside diameters of the package, and the inside flange 9 of the 95 ring-cover 8, are the same; and that the thickness of the package of the string-nails equals the distance between the inside of the ring-cover 8 and the inside base 4 of the container.

A hollow cylindrical bearing 15, Figs. 2, 3 and 4, is secured to the base 4 of the container and to the guide-plate 6 of the drum 5, for a supporting-rod, as 16, Fig. 1; which may, if desired, be fixed to a standard 17.

100 105 This rod 16 is intended to receive one or more of the above-described containers 1; the flange 7 of the drum of one container

abutting the bottom or base 4 of the adjacent cylinder, so that there is formed by the surfaces of the nail-guiding flange 7 and the ring-cover 8 of one container, and the base 5 of the adjacent container, a guide channel 18 for the string of nails being withdrawn from the container in question. When, however, there is only one container used, or when the outside container of a series is 10 used, then said container must be provided with a guide-plate 19 having a hub 20 mounted on the rod to serve as one side of the guide channel 18, required by each container.

15 In Figs. 2 and 3, is shown a package of coiled nails 2 inside of the container. Obviously, it with its bindings 21 may be inserted into the container, after the ring-cover 8 is removed. When the package is 20 in position, the ring-cover is replaced, and, when twisted, its clips 13 become interlocked with those 14 on the cylinder, and all is secure. By cutting the binding 21, through the opposite openings 22, the coils become 25 released, but are retained within the base 4, sides 3, and the ring-cover 8, of the container.

Packages of coils having nails of different lengths may be similarly mounted in their 30 respective containers, as upon the rod 16, Fig. 1; each container being capable of being turned on the rod, but its movement retarded by a spring member 23, pressed in between the rod and the bearing 15 of its 35 respective container.

To withdraw the nails from the container, rotatable as on the rod 16, Figs. 1 and 2, the freed end portion of the strand 12 is drawn out through the space 11, Fig. 2; the strand 40 being one of the inside rows of coils forming the inside face of the package 2 as shown in Fig. 3. As the strand is withdrawn, the container is moved against the resistance offered by the drag spring 26; the rear 45 smooth face of the strand slides out along the inside edge and face of the inner flange 9, while the saw teeth heads of the nails move unopposed over the nail-guiding flange 7. By means of these guiding 50 flanges, only the freed portion of one coil of nails can be withdrawn from the container, and it is impossible for the freed strand to become bent and very likely broken, as would be the case were the strand dropped 55 down upon the rod 16, say.

Upon the standard 17 is a bar-support 24, adjustably secured thereto by a binding screw 25. This bar has a hook 26 to support my nailing device 27 when not in use, and a number of spring fingers 28, between which may be held the free ends of those strands of string-nails not in use.

Obviously this bar 24 may be raised or lowered and there secured in a position to

suit the convenience of a standing or a sitting operator. 65

Having described my invention, its operation and advantages, and desiring to protect the same in the broadest manner legally possible, 70

What I claim is:

1. A container for a package of string-nails, comprising a hollow cylinder with a bottom or base; a bearing in its longitudinal axis whereby the cylinder may be rotatably mounted; a ring-cover removably secured to the open end portion of said cylinder and provided with an inwardly extending guide flange, at its inner edge; a circular plate with an outwardly extending nail-guiding flange, at its outer edge; said flanges being separated to form a circular outlet 75 from within said cylinder. 80

2. A container for a package of string-nails, comprising a hollow cylinder with a bottom or base; means, in its longitudinal axis, whereby the cylinder may be rotatably mounted; a ring-cover removably secured to the open end portion of said cylinder and provided with an inwardly extending guide flange, at its inner edge; a circular plate with an outwardly extending nail-guiding flange, at its outer edge; said flange being separated to form a circular outlet 90 from within said cylinder; and said container 95 having openings therethrough, to enable the cutting of the fastenings of the package when within the container.

3. A container for a package of string-nails, comprising a hollow cylinder with a bottom or base; means, in its longitudinal axis, whereby the cylinder may be rotatably mounted; a ring-cover removably secured to the open end portion of said cylinder and provided with an inwardly extending guide 100 flange, at its inner edge; a circular plate with an outwardly extending nail-guiding flange, at its outer edge; said flanges being separated to form a circular outlet 105 from within said cylinder; and the sides of the cylinder having openings therethrough, to enable the cutting of the fastenings of the package when within the container; a rod 110 upon which the container may be rotatably mounted; and means whereby a resistance 115 may be offered to the rotation of said container.

4. A container for a package of string-nails, comprising a hollow cylinder with a bottom or base; a bearing, in its longitudinal axis, whereby the cylinder may be rotatably mounted; a ring-cover removably secured to the open end portion of said cylinder and provided with an inwardly extending guide flange, at its inner edge; a circular plate with an outwardly extending nail-guiding flange, at its outer edge; said flanges being separated to form a circular 125

outlet from within said cylinder; a rod upon which the container may be rotatably mounted; one or more other like containers mounted upon said rod; the nail-guiding flange of the plate of one container, abutting the bottom of the adjacent container.

5 5. A container for a package of string-nails; comprising a hollow cylinder with a bottom or base; a bearing in its longitudinal axis whereby the cylinder may be rotatably mounted; a ring-cover removably secured to the open end portion of said cylinder and provided with an inwardly extending guide flange, at its inner edge; a circular plate with an outwardly extending nail-guiding flange, at its outer edge; said flanges being separated to form a circular outlet from within said cylinder; a rod upon which the container may be rotatably mounted; one or more other like containers mounted upon said rod; the nail-guiding flange of the plate, abutting the bottom of the adjacent container; a guide-plate removably secured to said rod, to abut the nail-guiding flange of the said plate of the last container of the series of containers.

10 20 25

6. A container for a package of string-nails, comprising a hollow cylinder with a bottom or base; a bearing in its longitudinal axis whereby the cylinder may be rotatably mounted; a ring-cover removably secured to the open end portion of said cylinder and provided with an inwardly extending guide flange, at its inner edge; a circular plate with an outwardly extending nail-guiding flange, at its outer edge; said flanges being separated to form a circular outlet from within said cylinder; a rod upon which the container may be rotatably mounted; one or more other like containers mounted upon said rod; the nail-guiding flange of the plate, abutting the bottom of the adjacent container; a guide-plate removably secured to said rod, to abut the nail-guiding flange of the said plate of the last container of the series of containers; a standard to sustain said rod and containers; and devices to hold the end portions of the freed strands of string-nails when not in use.

30 35 40 45 50
In testimony whereof I hereunto affix my signature.

JOHN P. DUBOSH.
